GUMMED TAPE DISPENSER

Alphonse D. Weigolt, Cleveland, Ohio

Application February 25, 1939, Serial No. 258,559

16 Claims. (Cl. 164—44)

The present invention relates to a device for dispensing gummed tape in the form of strips which are drawn or pulled off from a roll of the tape and adapted to be used for sealing and fastening packages, boxes, cartons and the like. Such gummed tape is customarily in the form of a paper strip having a coating of adhesive, such as glue, on one side. Devices for dispensing such gummed tape consist essentially of a chamber or receptacle for receiving the roll of tape, means for guiding a strip of the tape over a moistening device as it is drawn off from such roll, and a cutting device for severing the strip after the desired length has been pulled out of the dispenser and moistened. Examples of such prior devices are to be found in prior U. S. Patents Reissue No. 16,774, and Nos. 1,787,881 and 1,787,882.

It is the general object and nature of the present invention to provide a much improved construction for a gummed tape dispenser operating upon the foregoing general principles, and possessing the advantages of increased safety, economy, efficiency and flexibility of operation.

Specifically one of the primary objects of my invention is to provide an enclosing housing which not only protects the operating mechanism of the dispenser from damage, dirt and deterioration, but also protects the operator from likelihood of injury, particularly from cutting his fingers by inadvertent contact with the tape cutting blade.

Another primary object is to provide a tape roll receiving compartment or trough which is adapted to accommodate rolls of various widths and which also will permit the roll to be unwound easily and without undue friction as the strip is pulled out of the dispenser, but which at the same time will prevent the convolutions of the roll from becoming loosened, or the roll from unwinding itself.

Another primary object of the invention is to provide means for predeterminedly regulating the length of tape which can be withdrawn from the machine in a single operation. In conjunction with such measuring means the invention provides means for automatically resetting the measuring device to zero and in a position to repeat its operation immediately upon actuation of the cutting blade. In addition, indicating means is provided which continuously and instantaneously informs the operator of the exact length of strip which is being withdrawn from the dispenser.

The invention also provides an improved construction of water reservoir and brush means for

moistening the under side of the tape. Other objects and advantages shall become apparent as the following description proceeds.

To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:

Fig. 1 is a perspective view of the dispenser embodying the principle of the invention; Fig. 2 is a vertical sectional view of the dispenser; Fig. 3 is a top plan view, with the cover removed, of the tape delivery end of the dispenser; Fig. 4 is a fragmentary, vertical sectional view taken substantially along line 4—4 of Fig. 3; Fig. 5 is a detailed sectional view of the tape engaging friction roller and taken substantially along line 5—5 of Fig. 3; Fig. 6 is a detailed sectional view taken substantially along line 6—6 of Fig. 3; Fig. 7 is a detailed sectional view taken substantially along line 7—7 of Fig. 6; Fig. 8 is a detailed sectional view taken substantially along line 8—8 of Fig. 3; Fig. 9 is a detailed elevation, partially in section, of the stop wheel of the automatic measuring device; Fig. 10 is a detailed plan view of one side of the measuring wheel of the automatic measuring device; and Fig. 11 is a detailed sectional view of one of the tape roll receiving troughs and taken substantially along line 11—11 of Fig. 2.

Now referring more particularly to Figs. 1, 2, 3, 6 and 11, the device shown therein consists of a base housing member 1 with the cover member 2 overlying it and hingedly connected thereto as indicated at 3. The base member 1 has a pair of compartments or roll receiving troughs 4 and 5 which are parallel to and spaced from each other. As will be seen from Figs. 2, 3 and 6, the bottom walls of these troughs 4 and 5 are of curved contour, but their side walls are of different over-all widths.

A series of shoulders or steps 6, 7 and 8 are provided in the bottom portion of the troughs 4 and 5 (such steps being shown only in connection with the trough 4 in Figs. 2 and 11) between the juncture of the bottom and side walls of the troughs. The tops of the steps 6, 7 and 8 are parallel to the bottom wall of the trough and the sides of the steps 6, 7 and 8 are parallel to

the side walls. These last described steps 6, 7 and 8 are for the purpose of accommodating tape rolls of various widths. Thus, directing attention to Fig. 11, the distance between horizontally opposite steps can conveniently be made to be 1 $\frac{1}{2}$ in., 1 $\frac{3}{4}$ in., and 1 $\frac{1}{4}$ in. so that tape rolls of 1 in., 1 $\frac{1}{4}$ in. and 1 $\frac{1}{2}$ in. respectively can be accommodated by the trough 4 between the sides of the steps 6, 7 and 8. The over-all width of the trough 4 or the distance between its side walls can be made 2 $\frac{1}{2}$ in. so that a maximum width tape roll of 2 in. can be accommodated. Thus tape rolls of four different sizes can be used in a single receiving trough. Similarly, the corresponding steps in the larger trough 5 can be so dimensioned that tape rolls varying from 1 $\frac{1}{2}$ in. minimum size to 3 in. maximum size can be accommodated. A roller 9 is mounted transversely of the trough 4 (also in the trough 5, not shown) and the bottom of the latter has a recess or depression 10 for clearing such roller. The periphery of the roller 9, as will be seen from Fig. 2, extends slightly above the top of the uppermost step 8 so that it is adapted to be contacted by the bottom portion of a tape roll, outlines of the latter being indicated at R and R'. The roller 9 is located at such a point between the bottom of the trough 4 and the tape discharge end of the latter, as indicated by the guide boss 11, as to serve as a balance and bearing point during the unwinding of the tape roll, whether the latter be of the type which is so wound that the gummed side of the tape is toward the center or towards the outside of the roll. Regardless of the diameter and width of the tape rolls placed in the trough 4, they will all have the common vertical center line C. L. Thus the tape roll indicated at R, which is of the gummed-side-toward-the-outside type, will have its center at the point O. The radius A from the center O to the center of the roller 9 makes an acute angle with the common center line C. L. As the tape strip leading from the roll R is pulled away, the latter will be momentarily drawn in a left hand direction with respect to Fig. 2 and out of contact with the bottom of the trough 4, so that the weight of the roll R will be wholly supported by the roller 9. As soon as the pulling action on the tape is stopped, the roll R is permitted to roll in a right hand direction and back against the bottom of the trough. The upward curvature of the trough to the right of the center line C. L. stops any further rolling movement of the roll R.

In the case of the roll indicated at R', which is of the gummed-side-to-the-inside type having its center at O' with the radial line A' passing through the center of the roll 9 and making an acute angle with the center line C. L., a pulling of the tape off from the roll will also tend to move the weight of the latter up onto the roller 9 and off the bottom of the trough 4. As such pulling is stopped, any tendency of the roll R' to roll in a right hand direction will likewise be stopped by contact of the latter with the bottom of the trough 4.

Thus the provision of the roller 9 and its location with regard to the bottom of the trough and the center of the rolls R and R' operates to permit an easy and frictionless unrolling of the rolls, while at the same time any tendency to unwind or loosen the convolutions of the rolls is prevented due to the friction braking action as the latter moves back into normal position in contact with the bottom of the tape receiving troughs.

Adjacent the tape discharge end of the trough 4 there is located the guide boss 11 which has a bottom 12 corresponding with the bottom of the trough 4 and a series of steps 13, 14 and 15 whose contour corresponds to and is similar to that of the steps 6, 7 and 8. A similar guide boss 11' with a bottom 12' and steps 13', 14' and 15' is of course also provided adjacent the tape discharge end of the larger width trough 5.

10 A guide or feed plate 16 adapted to contact the under side of the tape strip is mounted on the base housing member 1. Projections 17 overlie the feed plate 16 and are spaced a sufficient distance from the latter to permit the passage of the tape strip. A space 18 is left between the projections 17 for the purpose of allowing the passage of the gripping tab cut out of and lifted up from the center of the tape strip.

20 The cover 2 carries a front wall casting 20 whose bottom surface, along with the contiguous upper guide plate 21 is also spaced from the surface of the feed plate 16 to allow the passage of the tape strip.

25 The cutter frame 22 is mounted upon the shaft 23 which in turn is journaled in the bosses 24 carried by the upper guide plate 21. The cutter frame is locked to the shaft 23 by means of a set screw 25. An operating handle 26 is located on the upper end of the cutter frame 22. The cutter frame 22 has a transversely extending portion 27 which carries the tape severing knife blade 28. The intermediate portion of the cutter frame 22 mounts the U-shaped tab cutting blade 29. A slot 30 is provided in the top wall of the cover 2 to receive the cutter frame 22. A slot or recess 31 is also provided in the front wall portion 20 to permit passage of the transverse bar portion 27 on the cutter frame 22. Referring to Figs. 1, 2 and 4, it will thus be seen that the cutter frame 22, 35 together with the cutting blades 28 and 29 is normally held in a position within the confines of the cover 2 so that the sharp, cutting edges of the blades 28 and 29 do not protrude where they might be contacted by the operator's fingers, and 40 are also protected themselves against dulling or damage by reason of possible contact with any hard object.

45 The cutter frame 22 is normally held in upright position by means of the coiled tension spring 32 which is anchored at one end in the boss 33 on the inside of the cover 2 and at the other end to the back of the cutter frame.

50 As will be seen from Figs. 1 and 3, a similar cutter frame structure indicated generally at 22' is provided adjacent the tape receiving trough 5 and mounted upon a separate shaft 23'. The cutter frame 22' is shown in full lines in Fig. 3 in fully depressed or cutting position.

55 An idler roller 35 is provided at a point between the guide boss 11 and the right hand end of the feed plate 16. A similar idler roller 35' is provided adjacent the base of the guide boss 11' of the roll receiving trough 5. Friction rollers 36 and 36' are mounted upon the common shaft 37. Rubber sleeves 38 and 38' are carried on the outside periphery of the friction rollers 36 and 36' respectively. Referring to Fig. 2, it will be seen that the tape strip T coming from the guide boss 11 passes between the rollers 35 and 36, and that the axes of the latter are located in a common plane with the point of initial contact of the tape strip T with the friction roller 36. Thus, the idler roller serves to hold the strip T in contact with a sufficient portion of 70 the periphery of the friction roller 36 so as to in-

sure the proper driving rotation of the latter as the tape is pulled out of the dispenser.

Directing attention to Fig. 5, both the friction rollers 36 and 36' are mounted upon the shaft 37 by means of a one-way clutch consisting of the rollers 39, mounted in the slots 40. Thus, rotation of the friction rollers 36 or 36' in a clockwise direction will operate to rotate the common shaft 37. Rotation of the friction rollers 36 and 36' in an opposite or counterclockwise direction will of course not be imparted to the common shaft 37.

A pinion gear 41 is carried by the common shaft 37 and meshes with the larger gear 42. The gear 42 is supported in one end of the arm 43 of a bell crank lever 44 pivotally mounted upon the common shaft 37 and having the other arm 45 whose end is adapted to contact with flats 46 and 46' on the juxtaposed ends of the shafts 23 and 23' respectively (see Figs. 3, 4, 7 and 8). A leaf spring 45' extends between the hub of the lever 44 and the upper side of the shaft 23, urging the arm 45 in upward direction.

The gear 42 meshes with the large gear 50 carried by the measuring wheel 51. The tape 25 length adjustment wheel or stop wheel 52 is mounted adjacent the measuring wheel 51 upon the supporting shaft 53, being separated therefrom by the washer 54. The shaft 53 is supported by the arms 55 extending upwardly and 30 at an angle from the upper guide plate 21. A coil spring 56 is mounted around the hub 57 of the measuring wheel 51 and anchored at one end to the latter through the pin 58 and at the other end by means of the pin 59 on the adjacent supporting arm 55. A stop pin 60 on the web of the measuring wheel 51 is in circumferential alignment with another stop pin 61 on the adjacent supporting arm 55.

A circular groove 62 is located in the face of 40 the measuring wheel 51 adjacent the stop wheel 52. The groove 62 is interrupted by the abutment rib 63. A lug 64 on the stop wheel 52 fits into the groove 62. The stop wheel 52 has an abutment rib 65 adapted to contact with the stop pin 66 on the adjacent supporting arm 55.

The inside face of the flange of the stop wheel 52 has a series of equidistantly spaced notches 66' which are adapted to be engaged by the end 50 of the detent spring 67 mounted by means of the fastening screw 68 on the inside of the cover 2. A depressing button or pin 69 extends through the cover 2 and contacts with the detent spring 67 for forcing the latter out of engagement with the notches 66'. The stop wheel 52 has a raised, milled edge as indicated at 70 to facilitate gripping by the operator's fingers in rotation and setting of the stop wheel.

A downwardly depending boss 71 is provided in the central portion of the upper guide plate 21 and has a tapered hole 72 adapted to receive the end of the locking pin 73 which threadably engages the base housing portion 1 as indicated at 74. A knurled knob 75 is provided on the outer end of the locking pin 73.

Referring to Figs. 1, 2, 4 and 6, it will be seen that a portion of the periphery of the wheels 51 and 52 extends out through an opening in the cover 2. Indicating numerals are marked on the outer faces of the flanges of the wheels 51 and 52 and their units preferably correspond to the inches of tape strip lengths drawn out of the machine. As will be seen from Fig. 1, indicating markers 76 and 77, in the form of arrows, are placed on the top of the cover 2 and adja-

cent each one of the dials 51 and 52 respectively.

A water reservoir 80 composed of a non-metallic, non-corrosive material such as hard rubber, Bakelite, molded plastic, glass or the like, is removably mounted in the base housing portion 1 and is held in position therein by means of the marginal flanges 81. Open sided brush holding compartments are formed in the reservoir 80 by means of the upstanding walls 82. An inner cover plate 84 is mounted in a reservoir 80 and has the lifting tab 85 and the downwardly extending leg portions 86 on each end which are adapted to contact with the bottom of the reservoir 80. The cover plate 84 of course also has openings to accommodate the brushes 87 and 88.

The brush 87 has a backing plate 89 and a positioning plate 90 whose upper end 91 fits over the top edge of the reservoir 80. As will be seen in Fig. 2, the backing plate 89 diverges from the positioning plate 90 and operates to hold the brush 87 in an upright vertical position and away from the wall of the reservoir 80.

A curved separating plate 92 is carried by the brush 88 and spaces the latter from the brush 87. A light leaf spring 93 is mounted between the brush 88 and the bottom of the reservoir 80 and tends to urge the brush 88 in an upward direction against the bottom or gummed side of the tape strip.

It has been found that the above described brush construction has a much more efficient moistening function than has heretofore been obtained by a single brush, even though of the same over-all size as that of the two separate brushes. A light lifting spring 95 has one end fastened by means of the screw 96 to the under side of the feed plate 16. The free end of the spring 95 extends through the opening 97 in the feed plate 16 and operates to raise up the grasping tab D. T. cut out of the tape strip T. The operation of the above described dispensing device is as follows:

The cover 2 is first thrown back. A roll of gummed tape having a width, for example, of 1½ in. is placed in the receiving trough 4 and will rest upon the steps 7 therein. Another roll of gummed tape of larger width is placed in the receiving trough 5. Both rolls are so placed that the gummed side of the tape T will be on the under side of the tape as it is laid over the boss 11. A sufficient length of tape is preliminarily drawn off of the roll so as to at least extend under the projections 11. The cover 2 is then moved into closed position and locked by means of the locking pin 73. The dispenser is now ready for operation, with the tape strip T of both rolls in both receiving troughs 4 and 5 passing over the bosses 11 and 11', between the idler rolls 35 and 36, 35' and 36', and between the feed plate 16 and the upper guide plate 21. The cutting frames 22 and 22' are then actuated to cut off the end of the tape strip and to form the grasping tabs. As either one of the strips are drawn by the grasping tabs out of the dispenser, they will cause either one of the respective friction rollers 36 or 36' to rotate the common shaft 37, and through the gears 41, 42 and 50, cause the measuring wheel 51 to rotate. When the desired length is indicated upon the dial of the measuring wheel 51 at a point opposite the indicating arrow 76, the operator stops pulling the tape strip and actuates the cutter frame 22 by grasping the manipulating handle 26 and swinging it downward to cut off the measured length.

of strip and to form another grasping tab. As either one cutter frame 22 or 22' is so actuated, the respective flats 46 or 46' on the end of the shafts 23 or 23' will depress the arm 48 of the bell crank lever 44 moving the gear 42 out of mesh with the gear 50. Such latter described position of the parts is illustrated in dotted lines in Fig. 8. As the gear 42 comes out of mesh with the gear 50, the coil spring 58 winds the measuring wheel 51 back to its original starting position or to a point where the stop pins 68 and 68' contact each other, which point corresponds to zero setting of the dial on the wheel 51. The above described cycle of operations may then be repeated, the measuring wheel 51 in each instance resetting itself to zero.

In the event that it is desired to predeterminedly regulate the lengths of tape strip which can be drawn out of the dispenser, the stop wheel 52 is then set to the corresponding length by means of depressing the button 69 and rotating the wheel to the reading opposite the indicating arrow 71. As the measuring wheel 51 is then rotated by reason of contact of the tape strip with either one of the friction rollers 36 or 36', it will be permitted to go only so far as the stop lug 64 contacts with the abutment 63 in the groove 62. At this point, both wheels 51 and 52 will indicate the same tape length reading. Since the wheel 51 can no longer rotate, it will likewise stop rotation of the gears 58, 42 and 41 and of either one of the friction rollers 36 or 36'. This stoppage of rotation of the friction rollers 36 or 36' will in turn prevent the tape strip from being pulled out any further. The cutter frame 22 or 22' corresponding to the particular tape strip which is pulled out at the time, is then actuated and the measuring wheel 51 returns to zero setting, just as hereinbefore described. The same pre-measured lengths of tape may be repeatedly withdrawn from the dispenser without resetting the stop wheel 52.

A third mode of operation of the dispenser is also possible. Assuming that the stop wheel is set to dispense a tape length of 10 in., for example, and that the operator desires to draw out a longer length of tape strip without bothering to adjust the stop wheel 52. In this instance, it will merely be necessary to actuate the other of the cutter frames 22 or 22' corresponding to the tape strip which is not at the time being dispensed. Such actuation will throw the gear 42 out of mesh with the gear 50 permitting the measuring wheel 51 to return to zero and a continued length anywhere up to 20 in., in this particular instance, can still be withdrawn from the dispenser. By the same token, if a length of over 20 in. and up to 30 in. is still desired, another actuation of the cutter frame will again reset the measuring wheel 51 to zero.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In a gummed tape dispenser, the combination of means for receiving a roll of tape, means for supporting and guiding a strip of tape withdrawn from said roll, means for indicating the length of said strip as it is manually withdrawn from said dispenser, a cut-off knife from severing such strip length, and means rendered effective

upon severing operation of said knife for resetting said indicating means to zero reading.

2. In a gummed tape dispenser, the combination of means for receiving a roll of tape, means for supporting and guiding a strip of tape manually withdrawn from said roll, means for limiting the withdrawable length of said strip, means for predeterminedly regulating the corresponding strip length at which said limiting means is operable, a cut-off knife for severing such strip length, and means rendered effective upon severing operation of said knife for releasing said limiting means.

3. In a gummed tape dispenser, the combination of means for receiving a roll of tape, means for supporting and guiding a strip of tape manually withdrawn from said roll, a cut-off knife pivotally mounted above said strip guiding and supporting means, a friction roller engaging said strip, a strip length indicating dial, means connecting said friction roller to said indicating dial, and means actuated by the pivotal movement of said cut-off knife for rendering said connecting means inoperative.

4. In a gummed tape dispenser, the combination of means for receiving a roll of tape, means for supporting and guiding a strip of tape withdrawn from said roll, a cut-off knife pivotally mounted above said strip guiding and supporting means, a friction roller engaging said strip, a strip length indicating dial, a gear train connecting said friction roller to said indicating dial, and a throw-out lever actuated by the pivotal movement of said cut-off knife for disengaging gears in said gear train.

5. In a gummed tape dispenser, the combination of means for receiving a roll of tape, means for supporting and guiding a strip of tape withdrawn from said roll, a cut-off knife pivotally mounted above said strip guide and supporting means, a friction roller engaging said strip, a shaft carrying said friction roller, a strip length indicating dial, a gear train connecting said shaft to said indicating dial, a bell crank lever pivotally mounting one of the gears in said gear train, and a cam actuated by said cut-off knife and engaging one end of said bell crank lever for moving said one of said gears out of engagement in said gear train.

6. In a gummed tape dispenser, the combination of means for receiving a roll of tape, means for supporting and guiding a strip of tape withdrawn from said roll, a cut-off knife pivotally mounted above said strip guide and supporting means, a friction roller engaging said strip, a shaft carrying said friction roller, a strip length indicating dial, a gear train connecting said shaft to said indicating dial, a bell crank lever pivotally mounting one of the gears in said gear train, a cam actuated by said cut-off knife and engaging one end of said bell crank lever for moving said one of said gears out of engagement in said gear train, and spring means for returning said indicating dial to zero reading upon such disengagement.

7. In a gummed tape dispenser, the combination of means for receiving a roll of tape, means for supporting and guiding a strip of tape withdrawn from said roll, a cut-off knife pivotally mounted above said strip guiding and supporting means, a friction roller engaging said strip, a strip length indicating dial, means connecting said friction roller to said indicating dial, means actuated by the pivotal movement of said cut-off knife for rendering said connecting means in-

operative, a second strip length indicating dial mounted adjacent said first indicating dial, means for adjustably setting and locking said second indicating dial according to a predetermined strip length, and limit stop means connecting said second indicating dial to said first indicating dial so arranged and constructed as to prevent further movement of said first indicating dial upon obtaining a reading corresponding to the predetermined strip length setting of said second indicating dial.

8. In a gummed tape dispenser, the combination of means for receiving a roll of tape, means for supporting and guiding a strip of tape withdrawn from said roll, a cut-off knife pivotally mounted above said strip guide and supporting means, a friction roller engaging said strip, a shaft carrying said friction roller, a strip length indicating dial, a gear train connecting said shaft to said indicating dial, a bell crank lever pivotally mounted one of the gears in said gear train, a cam actuated by said cut-off knife and engaging one end of said bell crank lever for moving said one of said gears out of engagement in said gear train, a second strip length indicating dial mounted adjacent said first indicating dial, means for adjustably setting and locking said second indicating dial according to a predetermined strip length, and limit stop means connecting said second indicating dial to said first indicating dial so arranged and constructed as to prevent further movement of said first indicating dial upon obtaining a reading corresponding to the predetermined strip length setting of said second indicating dial.

9. In a gummed tape dispenser, the combination of a plurality of means for receiving a roll of tape, means adjacent each of said receiving means for guiding and supporting strips of tape withdrawn from each roll, friction rollers engaging each of said strips, a common shaft for mounting said friction rollers, one way clutches connecting each of said rollers to said shaft, a strip length indicating dial, means for connecting said dial to said common shaft, cut-off knives pivotally mounted above each of said strips, and means actuated by the movement of said knives for disconnecting said last-named connecting means.

10. In a gummed tape dispenser, the combination of a plurality of means for receiving a roll of tape, means adjacent each of said receiving means for guiding and supporting strips of tape withdrawn from each roll, friction rollers engaging each of said strips, a common shaft for mounting said friction rollers, one way clutches connecting each of said rollers to said shaft, a strip length indicating dial, means for connecting said dial to said common shaft, cut-off knives pivotally mounted above each of said strips, means actuated by the movement of said knives for disconnecting said last-named connecting means, and means for returning said indicating dial to zero reading upon such disconnection.

11. In a gummed tape dispenser, the combination of a plurality of means for receiving a roll of tape, means adjacent each of said receiving means for guiding and supporting strips of tape withdrawn from each roll, friction rollers en-

gaging each of said strips, a common shaft for mounting said friction rollers, one way clutches connecting each of said rollers to said shaft, a strip length indicating dial, a gear train connecting said common shaft to said indicating dial, cut-off knives pivotally mounted above each of said strips, a bell crank lever mounting one of the gears of said gear train, and cams actuated by each of said cut-off knives and engaging said bell crank lever for moving said one of said gears out of engagement in said gear train.

12. In a gummed tape dispenser, means for supporting and guiding a strip of tape, a tape cutting device comprising a bar pivotally mounted at its inner end for movement to and from cutting positions, a handle carried by said bar at its outer end, a transversely extending cutting knife adjacent said handle adapted to sever said tape upon movement of said bar to cutting position, and a tab-cutting knife mounted on said bar inwardly of said severing knife adapted to form a grasping tab on the unsevered portion of the tape upon operation of said severing knife.

13. In a gummed tape dispenser, means for supporting and guiding a strip of tape, tape cutting means comprising a tape severing knife and a tab forming knife, and actuating means for moving said cutting means to and from cutting position to sever said tape, said tab forming knife being adapted upon a severing operation of said actuating means to form a grasping tab on the outer end of the unsevered portion of the tape by which a subsequent strip of tape may be drawn over said supporting and guiding means.

14. In a gummed tape dispenser, the combination of means for receiving a roll of tape, means for supporting and guiding a strip of tape manually withdrawn from said roll, indicating means, driving means operable by the withdrawal of a strip of tape connected to said indicating means, means for severing the strip of tape withdrawn, and means operable to disconnect said driving means from said indicating means upon operation of said severing means.

15. In a gunmed tape dispenser, the combination of means for receiving a roll of tape, means for supporting and guiding a strip of tape manually withdrawn from said roll, means for limiting the withdrawal length of strip, driving means operable by the withdrawal of a strip of tape connected to said limiting means, means for severing the strip of tape withdrawn, and means operable to disconnect said driving means from said limiting means upon operation of said severing means.

16. In a gummed tape dispenser, the combination of means for receiving a roll of tape, means for supporting and guiding a strip of tape manually withdrawn from said roll, means for indicating the length of strip as it is withdrawn from said dispenser, means for limiting the withdrawable length of strip, driving means operable by the withdrawal of a strip of tape connected to said indicating means, means for severing the strip of tape withdrawn, and means operable to disconnect said driving means from said indicating means upon operation of said severing means.

ALPHONSE D. WEIGOLT.
